AIR-BRAKE TESTING APPARATUS

Robert Simpson, Newell, Pa.

Application March 19, 1938, Serial No. 196,943

5 Claims. (Cl. 73—51)

My invention relates to the testing of fluid-operated brakes, particularly air brakes, and more particularly the air brakes of railroad trains. The invention consists in improvements in apparatus, by virtue of which the tests may be made more readily and quickly.

The invention will be described as practised in testing the air brakes of railroad trains.

As those familiar with the art know, each railroad car is equipped with brake apparatus which is adapted to be operated by air under pressure. In general, such brake apparatus includes an auxiliary reservoir for compressed air, two pneumatic plungers, triple valves, retaining valves, and a brake-pipe, all organized and interconnected in known way to operate the brakes of the car. In service, the brake-pipes of the cars of a train are interconnected, by means of flexible coupling hoses, and provide a continuous air passage, known as the train-pipe, that extends from one end of the train to the other. At the head end of the train this train-pipe communicates through the usual engineer's brake valve with a main reservoir of compressed air, and at the rear end of the train the train-pipe is closed. The main reservoir, constantly supplied with air by a compressor in the engine, charges the train-pipe and auxiliary reservoirs and valves of the several cars with air at normal operating pressure—seventy pounds, pressure in the case of freight trains and one hundred and ten pounds in the case of passenger trains, and when the train-pipe is charged with air at such pressure, the brakes of all the cars stand in release positions. When the pressure in the train-pipe is reduced, the brake apparatus of the several cars operate to apply all brakes of the train. The brakes are held in applied positions until the air pressure in the train-pipe is restored to normal value, or substantially so. This control of the pressure within the train-pipe is effected in known way through manipulation of the engineer's brake valve.

When a train is made up in a terminal, and sometimes when a train out on the road is at rest in a station, it is required that the brakes of each car shall be tested and inspected. In making such test the train-pipe is connected through a testing apparatus arranged at one end of the train of cars to a supply of compressed air, and the auxiliary reservoirs and the train-pipe of the coupled cars are charged with air until normal operating pressure is established. Then communication between the air supply and the train-pipe is interrupted, and with the

aid of a pressure gauge in the testing apparatus and a watch the rate of air leakage in the brake system of the train is checked. If the leakage is within permissive tolerance, the inspector vents air from the testing apparatus until the pressure in the train-pipe is reduced twenty pounds, with the consequence that a service application of the brakes is effected. While the brakes are thus set, the inspector goes the length of the train, observing each brake to see that it has operated properly. Then he returns to the testing apparatus at the head end of the train and re-establishes communication between the supply of compressed air and the train-pipe, and recharges the train-pipe to normal operating pressure. This releases the brakes. Again the inspector walks the length of the train, looking at each brake to make sure that it is in proper release position. Upon completing the test, the inspector returns to the head end of the train, disconnects the testing apparatus, and makes his report. Thus it will be understood that in making the test the inspector must travel the length of the train four times. The time consumed and the cost are great, even when two inspectors work together on the job, and the problem is becoming more acute with the growing practice of operating freight trains of a mile or more in length.

My invention consists in refinements in testing apparatus, by virtue of which it is necessary for the inspector to go the length of the train only once and return. More particularly, I provide means in the testing apparatus for recharging the train-pipe and releasing the brakes, while the inspector, having gone the length of the train and inspected the brakes in applied positions, is still at the remote end of the train. The means are responsive to a drop in train-pipe pressure to a value below that which effects a service application of the brakes. Thus, it is merely necessary for the inspector, upon reaching the remote end of the train, momentarily to vent the train-pipe and then close it again. The testing apparatus at the head end of the train operates to recharge the train-pipe in the manner mentioned.

In the accompanying drawings testing apparatus embodying the invention is illustrated. Fig. I is a view in side elevation of a relatively simple form of the apparatus, with the means for supplying compressed air, and a train of cars, illustrated diagrammatically and to smaller scale; Fig. II is a fragmentary view, showing partly in side elevation and partly in vertical

section a portion of the apparatus to larger scale, and illustrating a modification in detail; Fig. III is a view in side elevation of a more refined form of testing apparatus in which the invention has 5 been embodied; and Fig. IV is a fragmentary view of such apparatus, as seen in plan from above, on the plane IV—IV of Fig. III; and Fig. V is a view, partly in side elevation and partly in vertical section, of the testing apparatus of 10 the invention embodying still other modifications.

Referring to the drawings, the brake-testing apparatus shown in Fig. I includes in a tubular body B, constructed in this case of standard 15 pipe fittings, and provided at its opposite ends with hose couplings 3 and 4, by means of which the apparatus may be connected in usual way in a line L of flow from a reservoir R of compressed air to the train-pipe TP of a train of cars T 20 whose brakes are to be inspected and tested. An air compressor C maintains the supply of compressed air in reservoir R at a pressure in excess of the normal train-pipe pressure (70 pounds or 110 pounds, as already mentioned), and it will 25 be understood that the reservoir and compressor may be the main reservoir and compressor of the locomotive which is to pull the train. Alternately, the reservoir and compressor may, as here shown, consist in a permanent piece of apparatus in the railroad yard in which trains are made up and inspected.

In accordance with the invention, the testing apparatus includes a two-branched line of flow from the air reservoir to the train-pipe. One 35 branch of such line of flow is provided in the tubular body portion to which the reference letter B is immediately applied, and in this branch two pressure gauges 1, 1 and a manually operated valve 2 are provided, with a flow-constricting cone 40 5 (or an orifice plate) included between the gauges, to prevent undue violence of flow when the valve 2 is opened and air is charged from the reservoir R into the train-pipe TP. The second branch of such line of flow is provided 45 in pipe sections 6, 7, and 8, connected together in the form of an inverted U, and assembled in the apparatus in such manner that the gauges 1, 1 and the valve 2 lie between the legs of the U. An auxiliary valve 9 is included in this second 50 branch, and it will be perceived that by opening such valve, communication may be established between the air reservoir R and the train-pipe TP, whether or not the valve 2 is open or closed. The invention consists in instrumentalities that 55 are responsive to the control of the inspector, when he is at the remote end of the train, for opening the auxiliary valve 9.

Such instrumentalities include yielding means 60 that tend to turn the valve 9 from closed to open position, and means for normally holding the valve, against the urging of said yielding means, in closed position until the air pressure in the train-pipe is intentionally reduced to a value below that which effects a service application of 65 the brakes being inspected. In the apparatus of Fig. I, such yielding means consist in a spring 10, tending to swing the operating handle 11 of the valve 9 counter-clockwise from the horizontal position illustrated, in which the valve is closed, 70 into a vertical position, in which the valve is open; and the means for holding the valve in closed position consist in a trip-arm 13 which is pivoted at its lower end to a rigid bar 12 that spans the pipes 6 and 8. The upper, distal end of the trip-arm 75 is adapted to engage the outer end of the

handle 11 from beneath and hold the valve against the tension of spring 10 in closed position. A plunger rod 15 in a cylinder 16 is movable in response to an intentional reduction in pressure in the train-pipe, to swing the trip-arm from engagement with the handle 11 and permit the spring 10 to open the valve. Further detail in the structure and operation of the apparatus will be considered in the ensuing description of a 10 brake inspection.

Preparatory to making an inspection, the upper hooked end of the spring 10 is disengaged from the pin 31 that secures it to the operating handle 11 of valve 9, and both valve 9 and valve 2 are closed. The testing apparatus is then connected in line L between the reservoir R and the train-pipe TP. When this has been done, the valve 2 is opened and air is fed from the reservoir R into the train-pipe, until the gauges 1, 1 indicate that the pressure in the train-pipe and 15 brake system of the train has reached normal operating value, 70 pounds in the case of the illustrated freight train. Such charging of the system operates to release the brakes of the train.

The pressure existing in the train-pipe and 20 line L is effective through branch pipe 8 and pipe fittings 17 upon the left-hand face of a piston 18 (Fig. II) which is secured within cylinder 16 to the end of plunger rod 15. Between the piston and the head 19 of the cylinder a compression spring 20 opposes movement of the piston and rod under the influence of such air pressure. While air is being initially charged into the 25 system, the rising pressure gradually shifts the piston to the right; when the rising pressure reaches 20 pounds, a shoulder 150 on the shifting piston rod comes to position against the cylinder head 19, and arrests the movement of the piston; in such position of the piston the spring is 30 fully energized. As already mentioned, the charging of the system is continued until the pressure reaches the value of 70 pounds and the valve 2 has been closed. The plunger rod 15, projecting from cylinder 16, extends with sliding fit 35 through the trip-arm 13, and at its outer end carries a block 21. When the parts have come to rest, under the conditions described, the trip arm 13 is set beneath the valve handle 11, and the spring 10 is expanded and its free end hooked upon the pin 31 on the handle. The positions 40 of the parts at this stage of the operation are shown in Fig. I, it being noted that the block 21 lies at an interval to the right of the trip-arm. All is in readiness to proceed with the test. The inspector opens a normally closed angle-cock 45 22 and releases air from the charged system, until the gauges show a 15 pound drop in pressure; that is, until the pressure in the train-pipe is reduced to 55 pounds in this case. The angle-cock is then closed and the gauges are watched 50 for one minute, to note the pressure loss in the system. If the loss exceeds seven pounds in such interval of time, the inspector cannot approve the train for road service, but must find the source, or sources, of leakage and make necessary repairs. If the loss is less than this critical limit, a limit fixed by law, the inspector goes forward with the test. (It may be remarked that some railroads have voluntarily set five pounds per minute as the limit of leakage which will be 55 permitted.)

The angle-cock 22 is again opened and the pressure is permitted to fall to a value of 50 pounds, at which pressure the brake apparatus of the several cars of the train operate to effect 75

a service application of the brakes. Then the angle-cock 22 is closed. With the apparatus thus adjusted, the inspector goes the length of the train and inspects the brakes of each car to make

5 sure that they have properly responded to the brake-applying reduction in train-pipe pressure.

Upon reaching the remote end of the train, and having completed his test of the applied brakes, the inspector momentarily opens the usual

10 angle-cock at the rear end of the caboose, or last car of the train, and effects a reduction in the train-pipe pressure below the critical value of 20 pounds at which the spring in cylinder 16 is fully compressed. This fall in pressure in the

15 train-pipe relieves the pneumatic pressure on the piston 18 in the testing apparatus at the head end of the train, with the consequence and effect that the spring 20 expands and shifts the piston 18 and rod 45 to the left. The 11, 12, 13

20 and rod 15 to the left. The block 21 on the shifting rod 15 moves into contact with the side of the trip-arm 13, and swings such arm in counterclockwise direction. The distal end of the trip-arm is thus disengaged from the valve-operating handle 11 (cf. broken line position in Fig. 11).

25 handle 11 (cf. broken-line position in Fig. II), and the handle, under the stress of spring 10, swings downward and opens the valve 9. Thereupon, branch line 6, 7, 8 of flow is opened and communication is established between the supply

30 Communication is established between the supply R of compressed air and the train-pipe, and the train-pipe is recharged to the pressure of the air supply, which is equal to, or in excess of, the pressure (70 pounds) necessary to effect the release of the safety valve.

of the brakes. When the brakes of the train have thus been released, the inspector returns along the length of the train and checks each brake, making note of any that have not operated properly. Upon reaching the head end of the train, the

40 ery. Upon reaching the head end of the train, with the inspection completed, the testing apparatus is disconnected and the customary report made to the yardmaster or other supervisor. Thus, it will be perceived that my apparatus

time, it will be perceived that my apparatus makes for substantial savings in time and labor; it eliminates the need of two men to do the job, and does not require signaling between the head end and rear of the train.

It may be remarked that, if the train being inspected is a long train, there is a possibility that the leakage of pressure from the system may, while the attendant is making his inspection, with the brakes applied, cause the pressure in

60 with the brakes applied, cause the pressure in the train-pipe to fall below the brake-applying pressure of 50 pounds, in such manner that the trip-arm 13 will be thrown and the valve 9 opened before the end of the train is reached.

55 opened before the end of the train is reached. In order to prevent such an occurrence, the main valve 2 may be allowed to stand in slightly open position, to permit the reservoir to supply air to the system in quantity equal to that lost by

leakage. Thus, the pressure in the train-pipe may be maintained at brake-applying value, until the inspector reaches the end of the train and vents the train-pipe.

Another feature of adjustment is to be noted. The block 21 is adjustable axially of the piston rod 15, to the end that the valve-releasing movement of the trip-arm may be accurately responsive to desired critical value of pressure relief in the train-pipe. Conveniently, the rod and the block are threaded, whereby the block may be rotated to effect such adjustment.

The spring 16 and the plunger 15 are exemplary only of the means for achieving the ends in view. In modification, the operating handle of the valve 9 may be counter-weighted, as shown 75 at 10b in Fig. II, and needless to say the designer

may provide other known sorts of motors to effect the desired release of the valve-operating handle, so that the counter-weight (or spring) may operate to open the valve.

In Figs. III and IV, a refined and more compact embodiment of the invention is illustrated. In this refined structure, as in the structure first described, couplings 3a and 4a are provided for connecting the apparatus in the line of flow between the air reservoir and the train-pipe. Between the couplings 3a and 4a, the line of flow through the apparatus includes two branches, one branch through the body of a valve 9a, and the other through inter-connected pipe sections 6a, 7a, and 8a. The apparatus includes a gauge 1a arranged to indicate pressure in the line of flow, on each side of the valve 9a. It will be understood that, save for the connections 6a, 7a, 8a and certain additional parts presently to be described, the structure illustrated in Figs. III and IV is a piece of apparatus well known to the art.

A manually operated valve 2a controls flow in one branch of the double line of flow, and valve 9a controls flow in the other. The operating handle 11a of the valve 9a is provided with a lug 11b, and the distal end of a pivotally supported trip-arm 13a, which is backed by a leaf-spring 14b, is adapted to engage the lug 11b and lock the handle 11a, against the tension of a spring 18a, with the valve in closed position. Within a vertical cylinder 16a, a compression spring 20a exerts a thrust upon the upper face of a piston 18a, tending to shift the piston downward; a plunger rod 15a, secured to the piston and projecting from the upper end of the cylinder, extends with sliding fit through the trip-arm 13a, and above such trip-arm carries a block 21a; the lower end of the cylinder 16a communicates with the line of flow on the train-pipe side (the right-hand side) of the valve 2a, and air at train-pipe pressure, acting on the bottom of the piston 18a, opposes the thrust of the spring above.

The procedure in making a test is the same as that already described, and it remains only to say that a relief valve 22a (or other suitable means) is provided on the train-pipe side of the valve 2a, so that in the initial stages of the test the charged system may be vented to the open atmosphere, to reduce the train-pipe pressure from brake-releasing to brake-applying value. When the inspector has gone the length of the train with the brakes applied, he momentarily vents the train-pipe, with the consequence and effect that the spring 20a expands, the plunger rod 15a descends, the trip-arm 13a swings downward, the handle 11a rotates under the stress of spring 10a and opens valve 9a, and air at supply pressure is charged into the brake system of the train. The brakes of the train are thus released and the inspector moves forward from the remote end of the train and completes his inspection.

Turning to Fig. V, still another embodiment of the invention is shown, but it will be understood that the general procedure of making a brake test is no different with the structure of Fig. V than with the structures of Figs. I to IV. In Fig. V the coupling 4c serves to connect the apparatus to the line leading to the supply of compressed air, and coupling 3c (fragmentarily illustrated) serves to make connection to the line leading to the train-pipe of the train to be inspected. Between the couplings 4c and 3c there is a two-branched line of flow. Pipe 6c (controlled by a 75

manually operated valve 2c) forms one branch, and pipe 50 (controlled by a slide-valve 9c) provides the other. And, as in the structures described, a gauge 1c and a manually operated relief cock 22c are arranged on the train-pipe side of the valve 2c.

The slide valve 9c is by a rod 9d connected to a plunger rod 15c; the plunger rod 15c carries two pistons—a piston 18c of relatively small diameter in a cylinder 16c, and a piston 18d of relatively large diameter in a cylinder 16d. Between cylinders 16c and 16d, a tubular housing 16e incloses the plunger rod 15c; within housing 16e a ring 30 is arranged; the plunger rod extends with sliding fit through this ring, and between the ring and the piston 18d a helical compression spring 20c is organized, as shown. The ring 30 carries on each of its two diametrically opposite sides a pin 31, and each pin 31 extends radially outward through a slot 32 formed in the side wall of housing 16e. A second ring, a ring 33, is by a screw 34 secured externally upon the housing 16e, and the right-hand edge of this ring 33 provides an abutment against which the projecting ends of the pins 31 bear. Thus, the ring 30 within the housing is secured against axial displacement in right-to-left direction, and the compressed spring 20c, held captive between the ring 30 and the plunger 18d, tends to move the plunger assembly 15c, 18c, 18d to the right and shift the slide-valve 9c into open position. The position of the internal ring 30 may be adjusted axially of the plunger assembly, to regulate the magnitude of spring pressure on the piston 18d, and such adjustment is effected by varying the otherwise fixed position of the external ring 33 axially of the housing 16e.

When the apparatus is in service, the piston 18c is, manifestly, subject on its left-hand face to air at supply pressure, and piston 18d is subject on its right-hand face to air at train-pipe pressure. When the brakes are set in applied positions, both the manually operated valve 2c and the slide-valve 9c are closed, and the pressure of the air on the left face of piston 18c and the thrust of spring 20c of the left face of piston 18d are opposed and equalized by the pressure of air on the right-hand face of piston 18d. When the inspector has checked over the applied brakes, and momentarily vents the train-pipe at the remote end of the train, the pressure of air on the right-hand side of plunger 18d drops; the equilibrium of the forces acting on the plunger assembly 15c, 18c, 18d is destroyed, and the plunger assembly shifts in left-to-right direction, sliding the valve 9c into open position, with the consequence that air flows from the supply, through pipes 50 and 51, into the train-pipe. Thus, the train-pipe is recharged and the brakes shifted into release positions while the inspector is at the remote end of the train. From this point on, the test is completed in the usual way.

It will be perceived that in each of the structures described means are provided for shifting from closed to open position a valve (9, 9a or 9c) in one of two lines of flow. In the structure of Fig. I such means consist in the spring 19, in that of Fig. III in the spring 16a, and in that of Fig. V in the spring 20c and the piston 18c which is subject to air at supply pressure. And in each of the structures, I provide means subject to train-pipe pressure for holding the valve, against the urging of such shifting means, in

closed position. In the structures of Figs. I to IV, the valve-holding means consist in a trip-arm 13 or 13a, together with a plunger 15 or 15a, subject to spring pressure in one direction of movement and train-pipe pressure in the opposite direction, for throwing the trip-arm into release position when the train-pipe pressure is reduced below a critical value. And in the structure of Fig. V the means for holding the valve 9c in closed position consists simply in the piston 18d which, subject to the train-pipe pressure on its right-hand face, masters the forces tending to shift the valve into open position, until the train-pipe pressure is reduced below the critical value.

When the valves 9 and 9a of the structures of Figs. I to IV are released and shifted into open position, they stand in open position, regardless of train-pipe pressure, until they are manually reclosed. When the valve 9c of Fig. V is opened and recharging of the train-pipe begins, the rising pressure on the right-hand side of the piston 18d tends immediately to reclose the valve 9c. To the end that the valve, once opened, shall remain open until it is manually reclosed, I provide a spring-backed latch 35 that bears upon the plunger rod 15c; one or more notches 36 are formed in the plunger rod, and when in service the plunger assembly travels to the right and opens the valve 9c, notches 36 come to a position beneath the latch. The inner tip of the latch enters one of the notches and locks the parts against return movement, with the valve 9c in open position. When desired the latch may be manually withdrawn, and the valve 9c returned to closed position. In order to prevent undue violence in the operation of the plunger, an orifice-plate 5d is arranged in the line of flow between cylinder 16d and the air supply.

I claim as my invention:

1. In air-brake testing apparatus including a supply of compressed air, an air line adapted to establish communication from said supply to the train-pipe of a line of coupled cars whose brakes are to be inspected and tested, and a valve arranged in said air line; the herein described refinements in such apparatus which include valve-controlling mechanism including means for shifting said valve from closed to open position, means for securing said valve in closed position when air pressure in said train-pipe is above a critical value, and means adapted upon reduction of train-pipe pressure to a point below critical value to render said valve-securing means ineffective, whereby an attendant at the end of said line of cars remote from said apparatus may momentarily vent said train-pipe and effect the immediate opening of said valve and the recharging of the train-pipe to a pressure above said critical value.

2. The structure of claim 1, in which said valve-shifting means comprise a spring tending to shift said valve from closed to open position, and in which said valve-securing means comprise an element normally securing said valve, against the stress of said spring, in closed position, and a piston and means carried by the piston for throwing said element and releasing said valve to the stress of said spring, said piston being subject to train-pipe pressure on one side, and a spring exerting tension on said piston in opposition to train-pipe pressure.

3. In air-brake testing apparatus including a supply of compressed air, an air line adapted to establish communication from said supply to

the train-pipe of a line of coupled cars whose brakes are to be inspected and tested, a valve arranged in said air line, and means for shifting said valve from closed position to open position; 5
5 the herein described refinements in such apparatus which include a device that, subject to train-pipe pressure, is adapted to retain said valve in closed position when train-pipe pressure is above a critical value, and means adapted, 10 upon the reduction of train-pipe pressure to a point below critical value, to shift said device into valve-releasing position, with the effect that the valve, responding to the valve-shifting means mentioned above, is moved into open position, 15 whereby an attendant at the end of the line of cars remote from said apparatus may momentarily vent said train-pipe and effect the immediate opening of said valve and the recharging of the train-pipe to a pressure above critical 20 value.
4. In air-brake testing apparatus including a supply of compressed air, an air line including two branches adapted to establish communication from said supply to the train-pipe of a line 25 of coupled cars whose brakes are to be inspected and tested, a manually operated valve in one of said branches, a valve in the other of said branches, and means for shifting said last valve

from a position in which communication between air supply and train-pipe is interrupted to a position in which such communication is established; the herein described refinements in such apparatus which include a device that, subject to train-pipe pressure, is adapted to retain said last valve in closed position when train-pipe pressure is above a critical value, and means including a spring and a member movable under the tension of such spring that are adapted, upon 10 the reduction of train-pipe pressure to a point below critical value, to shift said device into valve-releasing position, with the effect that the last valve, responding to the valve-shifting means mentioned above, moves into open position, 15 whereby an attendant at the end of the line of cars remote from said apparatus may momentarily vent said train-pipe and effect the immediate opening of said valve and the recharging of the train-pipe to a pressure above critical 20 value.

5. The structure of claim 4, in which said device-shifting member consists in a piston subject to train-pipe pressure on one side, and a spring exerting tension on said piston in opposition to train-pipe pressure. 25

ROBERT SIMPSON.
